ABSTRACT OF THE DISCLOSURE

Hydrolyzed polyacrylonitrile is removed from an aqueous mixture consisting essentially of a quaternary ammonium salt, adiponitrile, acrylonitrile and hydrolyzed polyacrylonitrile by containing the mixture at a temperature up to about 45° C. and for at least about one hour to form an organic phase and a water phase, the phases separated by an interface (the interface not being definitely defined but consisting essentially of an emulsion which consists essentially of the hydrolyzed polyacrylonitrile), and withdrawing a portion of the interface and filtering said portion to remove the hydrolyzed polyacrylonitrile.

This application is a continuation-in-part of our co-pending application S.N. 618,248 entitled "Process of Removing Hydrolyzed Polyacrylonitrile From an Aqueous Mixture," filed on Jan. 30, 1967, and now abandoned.

BACKGROUND OF THE INVENTION

This invention relates to a process of removing hydrolyzed polyacrylonitrile from an aqueous mixture consisting essentially of a quaternary ammonium salt, adiponitrile, acrylonitrile and hydrolyzed polyacrylonitrile. More specifically, this invention relates to a process of removing hydrolyzed polyacrylonitrile from such an aqueous mixture by introducing the aqueous mixture into a decanter wherein the mixture is separated into an organic phase (comprising the adiponitrile and the acrylonitrile) and a water phase (comprising the quaternary ammonium salt), the phases separated by an interface (the interface consisting essentially of an emulsion containing the hydrolyzed polyacrylonitrile) and withdrawing a portion of the interface to separate the hydrolyzed polyacrylonitrile from the aqueous mixture.

Adiponitrile can be continuously produced by electrochemical dimerization of acrylonitrile to adiponitrile. This process is effected in an electrolytic cell containing at least one anode chamber and at least one cathode chamber, the chambers separated by an ion exchange membrane. In brief, the process comprises circulating an anolyte comprised of a dilute acid solution through the anode chamber, circulating a catholyte comprised of acrylonitrile dissolved in an aqueous quaternary ammonium salt solution through the cathode chamber, and establishing an electrical potential between the anode and the cathode sufficient to produce a unidirectional current flow and thus to reductively dimerize the acrylonitrile to adiponitrile at the cathode. The electrical potential causes the hydrogen ions of the dilute acid solution to migrate through the ion exchange membrane to make available the two hydrogen atoms required to dimerize acrylonitrile to adiponitrile. As the dimerization progresses a portion of the catholyte exiting from the cathode chamber is withdrawn and an equal portion of make-up quaternary ammonium salt solution containing acrylonitrile is added to the catholyte to maintain a constant volume catholyte stream.

2

The portion of the catholyte which is withdrawn from the catholyte stream contains water, quaternary ammonium salt, adiponitrile, acrylonitrile and a small quantity of by-products, e.g., propionitrile, bis-cyanoethylether, hydroxypropionitrile, etc., and a small quantity of hydrolyzed polyacrylonitrile. Adiponitrile, the desired product, is separated from the catholyte and the quaternary ammonium salt is returned to the electrolytic cell in the catholyte stream.

10 The quaternary ammonium salt employed in the catholyte of the electrolytic cell must serve two functions, i.e., the salt must provide ions in aqueous solution for conducting an electrical current and the salt must be capable of increasing acrylonitrile solubility.

15 Included among the suitable quaternary ammonium salts are tetraalkyl ammonium sulfates, tetraalkyl ammonium aryl sulfonates, and tetraalkyl ammonium alkyl sulfates. Two specifically useful salts are tetramethyl ammonium toluene sulfonate and tetraethyl ammonium ethyl sulfate. Any presently known quaternary ammonium salt will serve the two functions above described. Any presently known quaternary ammonium salt, as an element of the catholyte stream, may be operated upon in accordance with this invention for the removal of hydrolyzed polyacrylonitrile.

20 For efficient operation within the electrolytic cell, the quaternary ammonium salt in the catholyte stream must be kept substantially free of harmful impurities. Such a harmful impurity is hydrolyzed polyacrylonitrile.

25 By hydrolyzed polyacrylonitrile is meant polyacrylonitrile in which dependent-CN groups on the hydrocarbon backbone have been sufficiently hydrolyzed, i.e., to —CONH₂, —CONH₄, and —COOH groups, to result in at least partial solubility of the polymer in the electrolyte.

30 The formation of such soluble polymeric material in the electrohydrodimerization of acrylonitrile and the undesirable results of the presence of such materials are well known in the art.

35 For example, small amounts of this harmful impurity, e.g., about 0.1% based on the weight of the catholyte stream, can cause deposits on the cathode and, as a result, substantially reduce the efficiency of the electrochemical dimerization of acrylonitrile to adiponitrile.

40 Various methods have been proposed for commercial removal of such impurities from the aqueous quaternary ammonium salt solution which is withdrawn from the catholyte of the electrolytic cell during electrochemical dimerization of acrylonitrile. Filtration, of course, can be accomplished when the hydrolyzed polyacrylonitrile has 45 been precipitated generally (as opposed to existence of a precipitate in an interface). An example of this method of removal is contained in U.S. Pat. No. 3,335,162. When removal is by general precipitation, it requires, of course, a filtration of the entire aqueous catholyte stream. Such 50 filtration requires a great deal of time and effort, and can be pointed out as a serious bottleneck in commercial continuous production of adiponitrile.

SUMMARY OF THE INVENTION

55 It is an object of this invention to provide a process of removing hydrolyzed polyacrylonitrile from an aqueous mixture consisting essentially of a quaternary ammonium salt, adiponitrile, acrylonitrile and hydrolyzed polyacrylonitrile.

60 Another object of this invention is to substantially reduce cathode fouling in an electrochemical cell used in the electrochemical dimerization of acrylonitrile to adiponitrile.

65 A still further object of the invention is to improve the efficiency of the electrochemical dimerization of acrylonitrile to adiponitrile.

Other objects of this invention will become apparent as the invention is fully developed within the specification.

These and other objects of this invention are accomplished by providing a process of removing hydrolyzed polyacrylonitrile from an aqueous mixture consisting essentially of a quaternary ammonium salt, adiponitrile, acrylonitrile and hydrolyzed polyacrylonitrile comprising containing the mixture at a temperature up to about 45° C. and at a pH of from about 2.5 to about 7.5 for at least one hour to form a water phase and an organic phase, the phases separated by an interface, and withdrawing a portion of the interface as the hydrolyzed polyacrylonitrile. The interface is not a definitely defined interface but is an emulsion of the organic and water phase and consists primarily of hydrolyzed polyacrylonitrile.

It is the discovery that it is possible to obtain an interface containing essentially all of the hydrolyzed polyacrylonitrile in the mixture, that certain conditions are critical to the formation of this interface, and the practical use of the interface in removing this deleterious impurity from the catholyte stream by removal of the interface and filtration of this limited amount, which constitutes the essence of this invention. Conditions of pH and temperature are critical. However, as a practical matter the pH conditions are normally met by the catholyte stream in ordinary electrochemical dimerization process well known in the art. Temperature conditions, however, must be adjusted. Above temperatures of about 45° C., the hydrolyzed polyacrylonitrile will disperse throughout the aqueous layer and not be accumulated at the interface although the interface may exist at temperatures above 45° C.

On a practical basis, this process is useful for removing hydrolyzed polyacrylonitrile from an aqueous mixture consisting essentially of a quaternary ammonium salt, adiponitrile, acrylonitrile, and hydrolyzed polyacrylonitrile and also for separating therefrom and refining the quaternary ammonium salt, the acrylonitrile and adiponitrile, the process comprising:

(1) Introducing into a decanter an aqueous mixture consisting essentially of a quaternary ammonium salt, adiponitrile, acrylonitrile, and hydrolyzed polyacrylonitrile wherein the mixture is separated into an organic phase (comprising adiponitrile and acrylonitrile) and a water phase (comprising quaternary ammonium salt), the phases separated by an interface consisting essentially of an emulsion containing the hydrolyzed polyacrylonitrile;

(2) Withdrawing a portion of the water phase and washing said water phase with acrylonitrile to extract any adiponitrile in the water phase and passing the acrylonitrile plus any extracted adiponitrile into the organic phase of the decanter, the water phase consisting essentially of refined quaternary ammonium salt;

(3) Withdrawing a portion of the organic phase and washing said organic phase with water to extract any quaternary ammonium salt in the organic phase and passing the water plus any extracted quaternary ammonium salt into the water phase of the decanter, the organic phase being essentially refined and consisting essentially of adiponitrile and acrylonitrile; and

(4) Withdrawing a portion of the interface and filtering the interface portion to remove hydrolyzed polyacrylonitrile and passing the filtrate into the water phase of the decanter.

This practical aspect of the process provides for the removal of hydrolyzed acrylonitrile, for the refining and separation of the quaternary ammonium salt and combination of the adiponitrile and the acrylonitrile.

DESCRIPTION OF DRAWING

The attached drawing shows the preferred embodiment of the process. It is to be understood that this drawing is not to be considered as a limitation of the invention, but is presented to show an assembly of equipment in which the process may be practiced.

Feed 2 of an aqueous mixture consisting essentially of a quaternary ammonium salt, adiponitrile, acrylonitrile and hydrolyzed polyacrylonitrile is passed into decanter 4 wherein the mixture is separated into an organic phase (comprising adiponitrile and acrylonitrile), a water phase (comprising quaternary ammonium salt), the phases separated by an interface (the interface not being definitely defined but consisting essentially of an emulsion of the organic phase and the water phase and consisting essentially of hydrolyzed polyacrylonitrile). The decanter is operated at a temperature up to about 45° C., and preferably from about 20-35° C., and the hold-up time of the liquid in the decanter is at least one hour. A portion of the interface is withdrawn by stream 6, passed through filter 8 wherein the hydrolyzed polyacrylonitrile is removed and the filtrate 10 is passed into the water phase of decanter 4. A portion of the water phase in decanter 4 is withdrawn by stream 12, passed through acrylonitrile scrubber 28 wherein the water phase is scrubbed with acrylonitrile stream 16 to remove any adiponitrile or acrylonitrile, the scrubber water phase leaves scrubber 28 by stream 14 as an aqueous solution of refined quaternary ammonium salt, and the acrylonitrile plus any extracted adiponitrile leaves scrubber 28 by line 18 and is returned to the organic phase of decanter 4. A portion of the organic phase in decanter 4 is withdrawn by stream 20, washed with water in water scrubber 30 to remove any quaternary ammonium salt, the wash water plus any extracted quaternary ammonium salt exits scrubber 30 by stream 26 and is returned to the water phase of decanter 4, and the washed organic phase leaves scrubber 30 by stream 22 as refined adiponitrile and acrylonitrile.

DESCRIPTION OF THE INVENTION

As previously mentioned, hydrolyzed polyacrylonitrile is undesirable in the catholyte stream of an electrolytic cell wherein acrylonitrile is dimerized to adiponitrile. Such hydrolyzed polyacrylonitrile decreases the efficiency of the dimerization by fouling the cathode and, if the hydrolyzed polyacrylonitrile is permitted to remain in the processing streams, it will form emulsions which adversely affect the extraction of the products in the exiting catholyte stream.

Hydrolyzed polyacrylonitrile can be removed from a catholyte stream, the catholyte stream consisting essentially of an aqueous mixture of a quaternary ammonium salt, adiponitrile, acrylonitrile and hydrolyzed polyacrylonitrile, by a process comprising containing the mixture at a temperature up to about 45° C. and for at least about one hour to form a water phase and an organic phase, the phases separated by an interface, and withdrawing a portion of the interface as the hydrolyzed polyacrylonitrile. Preferably, the mixture can be contained at a temperature within the range of from about 20-35° C. and for a time of at least about one hour. The organic phase comprises adiponitrile and acrylonitrile and the water phase comprises quaternary ammonium salt. The organic phase and the water phase is separated by the interface, the interface not being definitely defined but consisting essentially of an emulsion containing part of the organic phase and part of the water phase and consisting essentially of hydrolyzed polyacrylonitrile. Impurities, e.g., propionitrile, bis-cyanoethyl ether, hydroxypropionitrile, and other by-products obtained from the dimerization of acrylonitrile to adiponitrile are present in the organic phase and water phase, depending on the solubility thereof—generally speaking these impurities are not harmful to the process and are permitted to remain in the processing streams.

This being a physical separation phenomenon, the proportion of the constituents of the catholyte are not critical to this process for the removal of hydrolyzed polyacrylonitrile, except in the sense that if there should be less than about 0.01% based on the weight of the catholyte stream of hydrolyzed polyacrylonitrile in the catholyte

stream, there will be insufficient interface emulsion for a practical withdrawal and removal.

It is desired that the pH of the aqueous mixture in the decanter be within the range of from about 2.5 to about 7.5. Within this range the particle size of the hydrolyzed polyacrylonitrile is larger and thus facilitates filtration of the interface portion containing the hydrolyzed polyacrylonitrile. More preferably, it is desired that the pH of the mixture be within the range of 3.5-6.5.

The hold-up time in the decanter should not be less than about one hour in order to effect adequate separation of the aqueous mixture into an organic phase and a water phase and to allow the hydrolyzed polyacrylonitrile particles to move to the interface. The hold-up time is unlimited, but due to the economics of the process a minimum hold-up time is preferred.

The following example is presented to illustrate the invention. Where percents are used, it is based on weight unless otherwise specified.

EXAMPLES

Tetraethylammonium p-toluenesulfonate was prepared as follows: A mixture consisting of 200 g. (1 mole) of ethyl p-toluenesulfonate, 101 g. (1 mole) or triethylamine and 100 ml. of absolute alcohol was stirred at room temperature for 3.5 hours and then heated to 72° C. within 40 minutes. At this point an exothermic reaction occurred, and extraneous heating was discontinued and the mixture allowed to stand for 30 minutes. At the end of that time it was heated to reflux, and refluxing was continued for 6 hours. After being allowed to cool to room temperature, the solvents and any unreacted material was stripped off with an aspirator to obtain a residue which solidified. This was washed with absolute ether three times by decantation. After removing traces of solvent from the washed product with an aspirator, there was obtained as residue 296.8 g. of the substantially pure tetramethylammonium p-toluenesulfonate, M.P. 103-104° C.

amperes for the first hour, about 3.2 amperes for the second hour, about 3.4 amperes for the third hour, and an E.M.F. of 19.0 to 17.3 volts for the first hour and from 17.30 to 17.0 for the next two hours. At the end of the three hour period an electric current of 3.5 amperes was passed into the cell for an additional 30 minutes. The electrolysis was thus conducted at from 5.5 to 6.2 amps./dm.² and a total of 10.1 amp.-hrs. The temperature of the catholyte was maintained at 20.5° C. to 26° C. by employing a mixture of acetone and Dry Ice in the cooling jacket. During the electrolysis, a total of 3.0 ml. of glacial acetic acid was added to the catholyte to maintain the pH thereof just alkaline to phenol red.

Three portions of a catholyte stream obtained as above were introduced into separate decanters.

The conditions within the decanters, i.e., pH of the mixture, hold-up time of the mixture in the decanter, and temperature of the mixer in the decanter, are indicated in Table I. The aqueous mixture separates into an aqueous phase and an organic phase and an interface consisting essentially of an emulsion consisting essentially of hydrolyzed polyacrylonitrile separates the two phases. A portion of the interface is withdrawn from the decanter and the amount of hydrolyzed polyacrylonitrile filtered is indicated in Table I, the filtrate is returned to the aqueous phase in the decanter. Table I also indicates the percent hydrolyzed polyacrylonitrile removed by the process.

In yet another example, a catholyte stream from an electrolytic hydrodimerization process similar to that of Example 1, and utilizing the same materials and conditions, but in commercial quantities, was subjected to the three-phase operation referred to in the drawing and in the description of the drawing, this operation including conditions within the decanter as to pH, temperature and holdup time identical with that of Example 3. Table II shows by material balance at points corresponding to the numbers on the drawing, a virtually complete removal of polyacrylonitrile by the process of this invention.

TABLE I

Aqueous mixture	pH of aqueous mixture	Temp. of aqueous mixture (° C.)	Hold-up time in decanter (hrs.)	Pounds of hydrolyzed polyacrylonitrile		Hydrolyzed polyacrylonitrile removed, percent
				in aqueous mixture	Removed at filter	
1-----	5.0	28	9.7	3.97	3.76	94.5
2-----	5.5	25	3.8	2.72	1.38	50.5
3-----	5.3	35	2.3	2.28	1.31	57.2

NOTE.—These above data indicate that hydrolyzed polyacrylonitrile can be effectively removed from the aqueous mixture.

TABLE II.—MATERIAL BALANCE SHOWING POLYACRYLONITRILE REMOVAL FROM AN AQUEOUS MIXTURE

Component	Decanter feed (2)	Interface to filter (6)	Filter effluent (10)	Organic phase to scrubber (20)		Acrylonitrile scrubber solvent (16)
				78	78	
Tetraethylammonium p-toluenesulfonate	24,696	2,021	1,971	1,376	0	-----
Water	24,643	1,708	1,451	14,783	7,443	1,350

Adiponitrile	12,045	1,013	1,024	-----	-----	-----
Polyacrylonitrile	78	78	0	0	0	-----

A concentrated aqueous solution (4° Baumé) was prepared by dissolving the 296.8 g. of tetraethylammonium p-toluenesulfonate in 230.5 g. of water. This was employed in the electrolytic hydromerization of acrylonitrile, as follows:

Acrylonitrile (94.5 g.) containing a trace of p-nitrosodimethylaniline as stabilizer was added to 141 g. of said solution of the sulfonate to give a catholyte containing 40% by weight of acrylonitrile, based on the total weight of the catholyte. A platinum anode was placed in an Alundum cup containing, as anolyte, 30 ml. of said concentrated aqueous solution of the tetraethylammonium p-toluenesulfonate and immersed into a jacketed glass vessel containing the catholyte and 110 ml. of mercury as cathode. An electric current was then passed through the resulting cell for three hours at about 2.3

60 We claim:

1. A process of removing hydrolyzed polyacrylonitrile from an aqueous mixture consisting essentially of a quaternary ammonium salt, adiponitrile, acrylonitrile and hydrolyzed polyacrylonitrile at a pH of from about 2.5 to about 7.5 comprising containing the mixture at a temperature up to about 45° C. for at least about one hour to form a water phase and an organic phase, the phases separated by an interface, and withdrawing a portion of the interface as the hydrolyzed polyacrylonitrile.
2. The process of claim 1 wherein the temperature of the mixture is from about 20° to about 35° C.
3. A process of claim 1 wherein the pH of the mixture is from about 3.5 to about 6.5.
4. In a process for the continuous production of adiponitrile by electrochemical dimerization of acrylonitrile to

adiponitrile, wherein said dimerization takes place in an electrolytic cell containing at least one anode chamber and at least one cathode chamber, said chambers being separated by an ion exchange membrane, and wherein an anolyte comprised of a dilute acid solution is circulated through the anode chamber, and a catholyte comprised of acrylonitrile dissolved in an aqueous quaternary ammonium salt solution is circulated through the cathode chamber, and wherein an electrical potential is established between the anode and cathode sufficient to produce a unidirectional current flow and thus to reductively dimerize the acrylonitrile to adiponitrile at the cathode, and wherein the electrical potential causes the hydrogen ions of the dilute acid solution to migrate through said ion exchange membrane thereby making available hydrogen atoms which dimerize acrylonitrile to adiponitrile, and wherein as dimerization progresses, a portion of catholyte is withdrawn from said cathode chamber being concomitantly replaced by new catholyte, the improvement comprising:

- (1) introducing the catholyte into a decanter,
- (2) maintaining the catholyte in the decanter at a temperature of from about 20° C. to about 45° C. and at a pH of from about 2.5 to about 7.5 for a period of at least one hour, wherein the catholyte separates into an organic phase and a water phase, the phases separated by an interface; and
- (3) withdrawing a portion of the interface.

5. The process of claim 4 wherein the pH of the aqueous mixture in the decanter is within the range of from about 3.5 to about 6.5.

6. In a process for the continuous production of adiponitrile by electrochemical dimerization of acrylonitrile to adiponitrile, wherein said dimerization takes place in an electrolytic cell containing at least one anode chamber and at least one cathode chamber, said chambers being separated by an ion exchange membrane, and wherein an anolyte comprised of a dilute acid solution is circulated through the anode chamber, and a catholyte comprised of acrylonitrile dissolved in an aqueous quaternary ammonium salt solution is circulated through the cathode chamber, and wherein an electrical potential is established between the anode and cathode sufficient to produce a unidirectional current flow and thus to reductively dimerize the acrylonitrile to adiponitrile at the cathode, and wherein the electrical potential causes the hydrogen ions of the dilute acid solution to migrate through said ion exchange membrane thereby making available hydrogen atoms which dimerize acrylonitrile to adiponitrile, and

wherein as dimerization progresses, a portion of catholyte is withdrawn from said cathode chamber being concomitantly replaced by new catholyte, the improvement comprising:

- 5 (1) introducing the catholyte mixture into a decanter wherein said mixture is maintained at a temperature up to about 45° C. for at least one hour and wherein the mixture is separated into an organic phase and a water phase, the phases separated by an interface and the organic phase comprising adiponitrile and acrylonitrile, the water phase comprising quaternary ammonium salt and the interface consisting essentially of hydrolyzed polyacrylonitrile.
- (2) withdrawing a portion of the water phase and washing said water phase with acrylonitrile to extract any adiponitrile in said portion of water phase and passing the acrylonitrile plus any extracted adiponitrile into the organic phase of the decanter;
- (3) withdrawing a portion of the organic phase and washing said portion of the organic phase with water to extract any quaternary ammonium salt in the organic phase and passing the water plus any extracted quaternary ammonium salt into the water phase of the decanter; and
- (4) withdrawing a portion of the interface and filtering the interface portion to remove hydrolyzed polyacrylonitrile and passing the filtrate into the water phase of the decanter.

7. The process of claim 6 wherein the temperature of the aqueous mixture in the decanter is within range of from about 20° C. to about 35° C.
